COAL-WASHING APPARATUS

Application filed January 12, 1927. Serial No. 160,551.

Our invention relates to coal washing apparatus of the character in which a stream of water, preferably under constant pressure, is delivered into a tank or receptacle underneath an inclined screen onto which the coal to be washed is delivered, the water flowing upwardly through the said screen to effect separation of the coal from the refuse such as slate, stone, etc. The coal being of less specific gravity than the refuse is carried upwardly and is ultimately discharged through outlets provided therefor, while the refuse is discharged through an opening at or adjacent the lower edge of the screen. In the operation or working of apparatus of this character it is desirable that means be provided whereby the discharge of the refuse is automatically controlled, and that such control be dependent upon the condition of the material being washed or treated as to the amount or percentage of refuse which may be present therein.

The tank of the apparatus is divided into two compartments connected with each other by a passageway. The water in one of these compartments is practically quiescent while through the other a stream of water is flowing continuously to effect separation of the coal and the refuse matter. The top or level of the water in the first named compartment varies in height depending upon the resistance which may be offered to the flow of the said stream through the other of the said compartments. Such resistance varies with the percentage of refuse matter, including slate, stone, etc., of relatively great specific gravity which may be present in the coal which is being washed or separated. If the resistance to the flow of water upwardly through the second named compartment be increased the height of the water in the first named compartment rises while on the other hand if the resistance to such flow be decreased so that the water may flow freely through the said second named compartment the height of the water in the first named compartment drops to a lower level. Advantage may be taken of the variation of the height of the water in the first named compartment to control and regulate the discharge of the refuse material.

For the more successful operation of an apparatus of the character or type under consideration it is desirable that some means be provided for regulating the discharge of the refuse matter, such as slate, stone, etc., from the screen previously referred to after the same has been separated from the coal; hence, it is a general object of the present invention to provide means of novel construction for controlling and regulating the discharge of the refuse matter from the screen after the separation of the same from the coal, the specific gravity of the refuse matter being greater than that of the coal.

It also is an object of the invention to provide means for regulating the discharge of refuse from the separation compartment, the operation of which means is controlled by the condition of the coal to be washed as to the percentage of refuse matter, such as slate, stone, etc., therein.

Another object of the invention is to provide means of novel construction which is adapted to regulate the discharge of refuse material from the coal washing compartment, the operation of which means is controlled by the variation of the height of water in one of the compartments into which the tank of the coal washing apparatus is divided.

We shall not at this time undertake to enumerate all of the objects and the advantages of our invention, or which may be incident thereto, but various other objects and advantages thereof will be pointed out in the detailed description thereof which follows, or will become apparent therefrom.

In order that the invention may be readily understood and its manifold practical advantages more fully appreciated, reference should be had to the accompanying drawing in which we have illustrated different forms of convenient mechanical embodiments of the invention. However, it will be understood that the invention may be embodied in other forms of construction than that shown and that changes of various kinds and of different degrees of importance may be made within

the scope of the claims without departing from the said invention.

In the drawing,—

Fig. 1 is a view in vertical longitudinal section of a coal washing apparatus provided with the invention, the features of construction embodying the said invention being for the most part, shown in elevation;

Fig. 2 is a sectional plan view taken along the line 2—2 of Fig. 1;

Fig. 3 is a transverse sectional view taken on the line 3—3 of Fig. 1;

Fig. 4 is a view similar to Fig. 1 in which is shown a slightly modified construction embodying the invention; and

Fig. 5 is a horizontal view partly in section and partly in plan view taken along the line 5—5 of Fig. 4.

In the drawing we have shown a tank 1 of usual construction comprising a compartment 2 into which water is delivered from a pipe 3. The latter has connection with a pump (not shown) of any known construction to which water may be drawn through a pipe 4 from a tank 5. A screen 10 of any known construction is mounted within the tank 1 and extends across the compartment 2 a distance above the point of delivery of water from the pipe 3 into the said compartment so as to form a separating compartment which is located above said screen. The coal to be washed is delivered from a chute 11 into the compartment 2 onto the screen 10. The compartment 2 is provided in its upper portion with an adjustable baffle plate 15 of known construction and operation. The flow of the water upwardly through the compartment 2 through the mixture of coal and refuse (including slate, stone or the like) on the screen 10 effects separation of the former from the latter. The coal is carried upwardly over the top edge of the cross-wise extending plate 16 into a section having an angular longitudinally extending member 17 therein the opposite sides of which are inclined toward the opposite edges of the structure so as to direct the coal to the outlet passageways 20 and 21 at the opposite sides of the apparatus as shown.

It may be noted that the coal which escapes through the openings 20 and 21 is conducted or carried through chutes 22 which join to form a single chute 23 which conducts the same to its destination. These chutes are perforated so as to permit the water which flows out with the coal to fall on a cover 24 from which it is conducted into the tank 5 to which previous reference has been made. The coal discharge openings 20 and 21 are controlled by adjustable doors or gates in known manner, as shown.

In order to regulate and control the height of water in the compartment 2 and in the section into which the coal is delivered from said compartment after it has been cleaned, we have provided an opening 24^a in a side wall

of the tank structure which is adapted to be controlled by a door or gate 24^b, which may be elevated or lowered in known manner.

The tank is also provided with a compartment 25 which is separated from the section into which the cleaned coal is delivered by means of a partition 26 which extends across the upper portion of the tank structure. The compartment 25 is in direct communication with the compartment 2 through openings 27 and 29 only, and it is in communication with the water supply pipe 3 only through said openings, the separating compartment, and the bed of refuse material positioned therein. The opening 29 is a passageway through which the refuse previously referred to is discharged from the screen 10. For the purpose of varying the discharge opening 29 we have provided an adjustable gate member 30 of any usual known construction, the adjustment of which is effected by means of adjusting means indicated at 31 in known manner.

The refuse, after it passes through the discharge opening 29, flows or moves over a hinged plate or lip portion 35 which is unperforated and which is provided with upwardly extending sides 37 at its opposite ends. The said plate or lip 35 is hinged at its rear edge as shown at its rear edge as shown at 38 in Fig. 1 or as shown at 39 in Fig. 4. The refuse, after it is delivered finally from the forward swinging edge of the plate or lip 35, falls into a section or portion 40 of the tank structure from which it is removed by an endless conveyor 41 operating in known manner.

We have provided means of somewhat different construction in Figs. 1 to 3 and Figs. 4 and 5 for effecting swinging movements of the plate or lip 35 on its pivot. In Figs. 1 to 3 we have shown for this purpose a lever 45 pivoted intermediate its ends upon a pivot 46. The pivot 46 is mounted upon a stationary part of the tank structure. The rear end of the said lever is connected by means of a link 47 to the forward edge portion of the plate or lip 35. Such connection is made through the medium of a short projecting bracket 48. The opposite forward end of the lever 45 is connected to an upwardly extending float rod or bar 50, the upper end portion of which extends through a bracket plate 51 and is adapted to move or reciprocate therethrough. Mounted upon the upper portion thereof is a float 55 which is adapted to be adjusted into different positions thereon by means of adjusting nuts 56 located above and below the same as is clearly shown. It is quite apparent that by adjustment of these nuts in one direction or the other upon screw threaded portions of the bar or rod 50 the float 55 may be adjusted into different positions upon the said bar or rod. In order to limit the extent of movement of the rod or bar 50 we have provided the adjustable nuts 60 and 61 upon its upper end portion which

130

are located upon the opposite sides of the stationary bracket plate 51. It may be found to be desirable to limit the extent of the swinging movements of the hinged plate or lip 35 and this may be done by adjustment of either or both of the nuts 60 and 61 toward or from each other. By decreasing the distance between the nuts 60 and 61 by an adjustment of either or both thereof, the limit of movement of the rod or bar 50, as well as of the swinging movement of the hinged plate or lip 35 is decreased, and by increasing the distance between said nuts the limit of such movements is increased.

15 The float 55 previously referred to rests upon the water within the float compartment 25 and the water in the said compartment is in a comparatively quiescent state. In other words there is no stream of water flowing 20 through the compartment 25.

In Figs. 4 and 5 of the drawing we have shown a slightly modified construction of the means for regulating and controlling the plate or lip 35 which comprises a rod 62 connected at its lower end to a projection 63 which extends forwardly from the said plate or lip. The length of the rod 62 is rendered adjustable by means of a turn-buckle 64. The upper end of the rod is connected to one end 30 of a lever 65 pivoted intermediate its ends at 66 to a pivot pin upon a stud or projection 67, which extends upwardly from the top of the tank structure. The opposite end of the lever 65 is connected to the upper end of a float rod 35 68, which extends downwardly into the water in the compartment 25. The lower end of the said rod extends through a hole or opening in a plate bracket 69 and is thereby guided. A float 70 is adjustably mounted upon the said 40 rod and rests upon the top of the water in the compartment 25.

The rod 62 extends downwardly through a tube 71 which projects upwardly from the portion 17 to which previous reference has 45 been made. The arrangement as shown in Figs. 4 and 5 enables the location of the lower end portion of the rod 62 at or about the longitudinal center of the structure, and avoids the necessity of laterally bending the same, 50 as is the case with the rod 50 shown in Fig. 3.

In both forms of construction counter-balance weights 72 may be mounted upon the upper side of the floats 55 and 70 for the purpose of varying the weight to properly counter-balance the weight of the plate or lip 35 and of any refuse which may be present thereon. For instance, as has already been indicated, when the height of the water in the compartment 25 becomes lowered due to causes 55 hereinbefore stated, the weight of the float 70 and the parts associated therewith must be sufficient to overcome the portion of the structure on the opposite side of the pivot 46 or 60 66 as the case may be, and of the plate or lip 35 and the refuse thereon in order that the

same may be lifted into substantially horizontal position as shown in dotted lines in Figs. 1 and 4 in order that the refuse may be retained upon the said plate or lip. By adjusting the weight of the float by the addition 70 or removal of any or all of the weights 72 therefrom the desired balanced condition may be obtained.

In both forms of construction slush valves 78 and 79 are provided in the bottom of the 75 tank structure, and also in both forms of construction slush valves 80 and 81 are provided in the bottom of the tank 5.

These slush valves are for the usual purpose and need not be described or referred to 80 more at length.

It is preferable that the adjustable gate 30 previously referred to and shown in both forms of construction be provided with a flange 85 of considerable width which extends 85 inwardly and rearwardly therefrom so that it overlies the forward portion of the screen 10 in rear of the opening 29 through which the refuse previously referred to is discharged. The presence of this flange aids in 90 preventing the passage of coal through the refuse discharge opening 29, but as the provision of this flange constitutes no part of our invention we shall not refer further thereto.

In order that the invention may be more clearly and definitely understood it should be pointed out that in the operation of a washing apparatus of this character it is necessary from a practical standpoint that there be maintained at all times upon the hinged plate or lip 35 a bed of refuse 90 which generally is somewhat of the shape in cross section as indicated in Fig. 1 of the drawing. If such bed be not present the result will be 100 that as the operating conditions vary a considerable quantity of coal may be discharged through the opening 29 intended only for refuse matter. A method of operation or an apparatus which should permit or allow of such waste would be impractical. Hence the desirability of means for actuating and adjusting the plate or lip 35 to correspond and harmonize with the condition of the coal as to the percentage of refuse matter therein 105 110 115 in order that a bed of refuse matter may be maintained at all times upon the said plate or lip.

Assuming an operating condition in which there is a large percentage of refuse including slate, stone or other material relatively great in specific gravity, it will be found to offer greater resistance to the flow of water upwardly through the compartment to and through the body of material being treated. 120 As a result of such increased resistance it 125 will be found that the height or top level of the water in the compartment 25 (the lower portion of which is in communication with an intermediate portion of compartment 2) 130

will be increased. In consequence of such increase the float 55 or 70 will be moved upwardly to effect movement of the lever 45 about its pivot in a direction to permit or effect a downward pivotal movement of the plate or lip 35. Usually or generally the said plate or lip does not occupy a position lower or more greatly inclined than is illustrated in Figs. 1 and 4 of the drawings, but it may occupy a lower or more greatly inclined position.

Assuming now another condition in which the coal which is being washed contains either none or a very small percentage of refuse material the resistance offered to the upward flow of water through the compartment to and through the screen 10 would be substantially decreased. As a result of such decrease of resistance the height or top level of the water in the tank 25 would descend to a lower level in consequence of which the float 55 or 70 with the rod or bar 50 or 68 upon which it is mounted would descend, effecting upward movement of the rear end portion of the lever 45 or 65 to lift the pivoted or swinging plate 35 upwardly into a less inclined position than that shown. It may assume a substantially horizontal position and thereby retain the bed of refuse 90 thereon even though for a period no addition to such material is being made. If the bed of refuse material 90 were removed from the plate or lip 35 the result would be, as has already been indicated, that some coal, a greater or less amount, would be allowed to pass through the refuse discharge opening 29 whereby unnecessary waste would result.

The variation in the height of the water in the compartment 25 due to a variation in the resistance offered to the flow of the water upwardly through the compartment 2 is in accordance with a well known law of hydrostatics, and these applicants have made use of such variation in the height or top level of the water in the said compartment for automatically regulating and controlling the position of the plate or lip 35 and thereby controlling and regulating the discharge of the refuse material therefrom.

Although we have described our invention as applied to an apparatus for washing coal, we do not wish to be understood as limiting the same to an apparatus for that specific purpose, but on the contrary make claim to the same for the purpose of washing and separating material of any other character to or for which it may be adapted.

Having thus described our invention, what we claim and desire to secure by Letters Patent is,

1. In a coal washing apparatus, the combination of a tank comprising a couple of compartments through one of which water flows and in the other of which the water is contained in a more or less quiescent state, the

flow of water through the first named compartment operating to separate the coal from slate and other refuse matter of higher specific gravity than the coal, the said first named compartment having a screen bottom upon which the slate and other refuse matter settles and also having a front wall having an opening at the lower edge thereof through which the said slate and other refuse matter is discharged, said opening constituting a passage for water from the first to the second named compartment and through which the two compartments are in direct communication, the height of the water in the said second compartment varying with the percentage of slate and other refuse in the coal being washed, a hinged plate extending forwardly from the lower edge of the discharge opening for the slate and other refuse matter separated from the coal, and means adapted to be controlled by variation of the height of the water in the said second named compartment for adjusting the said hinged plate into different positions.

2. In a coal washing apparatus, the combination of a tank having two compartments through one of which water is adapted to flow and in the other one of which water is adapted to be contained in a more or less quiescent state, means for delivering coal with any refuse which may be present therein to the first named compartment and the height of the water in the second named compartment varying as the percentage of refuse in the said coal varies, the coal and the refuse being separated from each other by the action of the water thereon in the first named compartment, one wall of the said first named compartment being provided with an opening through which the refuse is discharged, said refuse discharge opening constituting a passage for water from the first mentioned compartment to the second, a hinged plate beyond said opening onto which said refuse is delivered, and means controlled by the variation of the height of the water in the second named compartment for varying the position of the said plate about its hinge axis.

3. In a coal washing apparatus, the combination of a tank having a plurality of compartments, one of said compartments being provided with a screen extending across the same a distance above the lower end thereof, which screen terminates at its forward edge adjacent an opening through the front wall of the said compartment, and means for delivering coal to be washed into the said compartment and onto the said screen, means for delivering water under pressure to the said compartment underneath the said screen, the said water flowing upwardly through the said screen and through the said compartment to effect separation of the coal from the refuse and the latter moving outwardly and through the said opening, a plate pivoted at

its rear edge in adjacent relation to the forward edge of the said screen, said plate projecting forwardly and being downwardly inclined and being adapted to receive the refuse from the said compartment, and another of said plurality of compartments containing water in a more or less quiescent state the height of which varies with the percentage of refuse in the said coal, the said opening 10 through the front wall of the first mentioned compartment constituting a refuse discharge and a passage for water from the said first mentioned compartment to the second, a float supported upon the top of the water in the said second compartment, and a connection 15 between the said float and the said pivoted plate whereby variation of the height of the water in the second named compartment causes variations in the angle of inclination 20 of the said plate, substantially as described.

4. In a coal washing apparatus, the combination of a tank having two compartments through one of which water is adapted to flow and the other one of which is adapted 25 to contain water in a more or less quiescent state, means for delivering coal to be washed into the first named compartment to be acted upon by the water flowing therethrough to effect separation of any refuse which may be 30 present from the coal, the height of the water in the second named compartment varying as the percentage of refuse varies, and the first named compartment being provided with an opening through which the refuse 35 separated from the coal is discharged, the said opening constituting a passage for water from the first named compartment to the second, a hinged plate onto which the said refuse is discharged, a lever pivoted intermediate its ends, means for connecting one end of said lever to the said pivoted 40 plate a distance from the hinge supports therefor, a float supported on the top of the water in the second named compartment, and means for connecting the opposite end of 45 the said lever to the said float.

5. In a coal washing apparatus, the combination of a tank comprising a couple of compartments, means for delivering coal to be washed into one of said compartments, 50 means for causing water to flow upwardly through said compartment to effect separation of any refuse which may be present from the coal, said compartment being provided with an opening through which the 55 separated refuse is discharged, said refuse discharge opening constituting a passage for water from the first to the second named compartment, a plate hinged on its rear edge 60 and supported in position to receive the refuse as it is discharged from the said compartment, the height of the water in the second named compartment varying as the percentage of refuse in the said coal varies, a lever pivoted intermediate its ends upon a 65 stationary pivot, means for connecting one end of said lever to the said plate a distance from the axis of its hinge, a bar having connection to the opposite end of said lever and extending upwardly through the water in 70 the second named compartment, means for holding the said bar in an upright position, a float mounted upon said bar which float is supported upon the top of the water in the said second named compartment, and means for adjustment of the float upon the 75 said bar.

6. In a coal washing apparatus, the combination of a tank comprising a plurality of compartments, means for delivering coal to be washed into one of said compartments, means for causing water to flow upwardly through the said compartment to effect separation of any refuse which may be present from the coal, said compartment being provided 80 with an opening through which the separated refuse is discharged, said refuse discharge opening constituting a passage for water from the first to the second named compartment, a plate hinged on its rear edge 85 and supported in position to receive the refuse as it is discharged from the said compartment, the height of the water in the second named compartment varying as the percentage of refuse in the said coal varies, a lever pivoted intermediate its ends upon a stationary pivot, means for connecting one end of said lever to the said plate a distance from the axis of its hinge, a bar having connection to the opposite end of said lever and extending upwardly through the water in 90 the second named compartment, means for holding the said bar in an upright position, a float mounted upon said bar which float is supported upon the top of the water in the said second named compartment, and means for limiting the extent of movement of the said bar under the influence of the said float. 95

7. A coal washing apparatus comprising a tank having a compartment provided with a screen plate which extends there-across, means for delivering coal to be washed into the said compartment onto the said screen plate, means for causing water to flow through said compartment and screen plate for effecting separation of the coal and the refuse substance which may be present therein, the said compartment having a discharge opening adjacent the front edge of the said screen plate through which the refuse substance is adapted to be discharged, a plate hinged at its rear edge in adjacent relation to the front edge of the said screen plate, the said plate extending forwardly from the said screen plate and the said opening, the said tank having a second compartment in spaced relation to the first named compartment, means providing a passageway between the bottom portions of the said compartments whereby water may pass 100 105 110 115 120 125 130

- from the first to the second named compartment, the water in the second named compartment being in a more or less quiescent state, and the water in the said passageway forming a liquid connection between the water in the two compartments so that the height of the water in the said second named compartment may vary with the resistance offered by the coal being treated in the first named compartment, and a float located in the second named compartment and having connection with the front edge of said hinged plate and operating to vary the position of the said plate to correspond with the variation in the top level of the water in the said second compartment to control the discharge of refuse substances from said plate.
8. A coal washing apparatus comprising a tank divided into two compartments in one of which the coal is adapted to be separated from refuse substance therein by the action of water in motion therein and in the other of which water is contained in a quiescent state, the first named compartment having a screen bottom on which the said refuse substance settles, the front wall of the first named compartment being provided with an opening through which the said refuse substance is discharged, the said opening also constituting a passage for water from the first to the second named compartment, a plate hinged at its rear edge to the said front wall adjacent the lower edge of said opening, a lever pivoted intermediate its ends upon the upper portion of the said tank, a rod having connection at its lower end to the forward swinging edge of the said hinged plate and at its upper end to the rear end of the said lever, a float rod having connection at its upper end to the front end of the said lever, said float rod extending downwardly into the second named compartment in which water in a quiescent state is contained and a float mounted upon the said float rod and resting upon the top of the water in the said second named compartment, the position of the said float and the parts having connection therewith being controlled by the height of the water in the said compartment.
- 50 9. In apparatus for washing coal to separate therefrom slate and other refuse of higher specific gravity than the coal, the combination of water supply means, a hydraulic separating compartment having a screen bottom through which water flows from said supply means to effect separation of the coal from the slate and other refuse matter, the said screen bottom constituting a support for the slate and other refuse matter settling thereon, a separate water containing compartment, the said first named compartment having a front wall provided with an opening at its lower edge through which the said slate and other refuse matter is dis-

charged, the said opening also constituting a passage for water from the first to the second named compartment, the water entering said passage being caused to pass first through slate and refuse upon the said screen bottom so that the height of the water in said separate compartment may vary with changes in the resistance to the flow of water through said separating compartment, and means controlled by said variation in the height of the water in said separate compartment for controlling the discharge of slate and other refuse from said separating compartment.

10. In apparatus for washing coal to separate slate and other refuse therefrom, the combination of water supply means, a hydraulic separating compartment having a screen bottom through which water flows from said supply means to effect separation of the coal from the slate and other refuse, the said screen bottom constituting a support for the slate and other refuse matter settling upon the bottom of the said hydraulic separating compartment, said hydraulic separating compartment having a front wall provided with an opening at its lower edge through which the said slate and other refuse is discharged, a separate water containing compartment, the said refuse discharge opening constituting a passage for water from the first to the second named compartment, the water in the said passage constituting a liquid connection between the water in the two compartments, the water entering the said passage being caused to pass first through the slate and other refuse upon the said screen bottom so that the height of water in the said second named compartment varies, float means for said separate compartment, said float means being controlled by the height of water in said second compartment, and means connected with said float means and controlled thereby for regulating and controlling the discharge of slate and other refuse from said separating compartment.

11. A classifier comprising a hydraulic separating compartment, liquid supply means connected to the bottom of the separating compartment, means providing a settled refuse discharge from said separating compartment, a water containing float chamber separate from said separating compartment, float means in said float chamber and means controlled by said float means to regulate the discharge of settled solids through said refuse discharge, there being liquid communication between said liquid supply means through said separating compartment and the settled material therein to said float water chamber whereby said float means regulates the discharge from said separating compartment, in accordance with the varia-

ble resistance to water flow afforded by said settled refuse material.

In testimony that we claim the foregoing as our invention, we have hereunto signed our names this sixth day of January, 1927.
